TAPE MEASURE BLADE

**Michel Quenot, Besancon, France, assignor to
Stanley-Mabo**

Filed Mar. 12, 1974, Ser. No. 450,396

Claims priority, application France Oct. 1, 1973

Term of patent 14 years

Int. Cl. D10—04

U.S. CL. D10—71

The figure is a top plan view of a tape measure blade showing my new design with portions shown broken away for convenience of illustration.

The bottom or underside of the tape measure blade is plain and unornamented.

I claim:

The ornamental design for a tape measure blade, substantially as shown and described.
